UNITED STATES PATENT OFFICE.

WILLIAM E. WARNER, OF HOUSTON, TEXAS.

FLOOR SURFACER, CLEANER, AND POLISHER.

970,583.

Specification of Letters Patent. Patented Sept. 20, 1910.

Application filed December 27, 1909. Serial No. 535,190.

To all whom it may concern:

Be it known that I, WILLIAM E. WARNER, citizen of the United States, residing at Houston, in the county of Harris and State 5 of Texas, have invented certain new and useful Improvements in Floor Surfacers, Cleaners, and Polishers, of which the following is a specification.

My invention relates to new and useful 10 improvements in a floor surfacer, cleaner and polisher.

The object of the invention is to provide a device of the character described for surfacing and cleaning floors of wood of every 15 kind, as well as grinding or polishing those of mosaic, marble or any other composition.

Another object resides in the provision of a mechanism for operating a plurality of cutting rollers which may be applied to the 20 surface to be smoothed either simultaneously or separately.

A further feature resides in the provision of cutting rollers surrounded with resilient cushions which serve as a base for sand 25 paper or some other similar material which is designed to be secured upon said rollers.

With the above and other objects in view, my invention has particular relation to certain novel features of construction and operation an example of which is given in this specification and illustrated in the accompanying drawings, wherein:—

Figure 1 is a side elevation of my complete device. Fig. 2 is a partial plan view 35 thereof. Fig. 3 is a sectional side elevation of the device showing the operative mechanism thereof. Fig. 4 is a partial plan view of the gear mechanism. Fig. 5 is a side elevation of the form shown in Fig. 4. Fig. 40 6 is a plan view of the foot pedals for operating the device. Fig. 7 is a perspective view of the connecting rods which connect the foot pedals to the operative levers. Fig. 8 is a plan view of the cutting roller. Fig. 45 9 is a partial sectional end view of the same.

Referring now more particularly to the drawings, wherein like numerals of reference designate similar parts in each of the figures, the numeral 1 refers to the supporting frame which comprises two suitable side members which are secured together by suitable cross braces.

Numerals 2 and 3 refer, respectively, to 50 conveying wheels which are designed to support the device and transport the same from place to place. The wheels 2 are

mounted on a suitable steering device 4 which is operated by hand lever 5, and the wheels 3 are rigidly mounted on shaft 6.

Suitably mounted on the frame 1 is a 60 motor 7 which is designed to provide the motive power for the mechanism.

At both the front and rear ends of the frame 1 transverse abrading rollers 8 and 9 are revolubly mounted. These rollers are 65 not mounted on the frame proper but are secured, respectively, to levers 10 and 11 which are pivoted to the side members 1 as shown in Fig. 1. These rollers 8 and 9 are constructed, preferably, of metal and have 70 a resilient covering 12 of rubber or some similar composition so as to provide a yieldable base for the sand paper or other cutting surface. They are further provided with a longitudinal depression 13 extending the 75 full length of the roller upon one side of which a small roller 14 is secured and opposing which is another roller 15 whose cross section presents a cam shaped appearance. These rollers do not project beyond the 80 surface of the abrading rollers and are so disposed, relative to each other, that one edge of the sand paper may be inserted between said rollers 14 and 15 and the body of the paper wrapped around said abrading roller 85 and the other edge also inserted between rollers 14 and 15 and then by a partial rotation of roller 15 the said edges will be gripped between said small rollers and the paper securely held in place, the roller 15 90 being held in its proper place by a rack and dog arrangement 16.

Upon the shaft of motor 7 is a gear wheel 17 which meshes with gear wheel 18 which is rigidly mounted on shaft 19 carried by 95 the frame work 1. The shaft 19 also carries a drive gear 20 which meshes with drive chain 21 which in turn meshes with gear wheels 22 and 23 carried respectively, by the shafts of the cutting rollers 8 and 9 and 100 drives said rollers. This chain is held against sagging by means of an idler pulley 24.

The abrading rollers 8 and 9 are partially 105 inclosed by hoods 25 and 26, which surround the upper portions thereof. The outer portions of these hoods are detachable as is shown in Fig. 3. From the center of these hoods suction pipes 27 and 28 lead, which unite in a common pipe 29. At the 110 upper portion of pipe 29 a suction fan is mounted, from the casing of which a dis-

charge pipe 31 leads and discharges into dust receptacle 32. This suction system, just described, gathers the dust from the cutting rollers and discharges the same into the dust receptacle and is operated by a suitable driving chain or belt connected with the motor 7 as shown in Fig. 1.

For the purpose of elevating and lowering the abrading rollers I have provided levers 33 and 34 the former of which is fulcrumed at the point 35 and is secured at its forward end to an inverted U shaped member 36, which embraces roller 8 and is secured to either end of the shaft thereof. The lever 34 is fulcrumed at the point 37 and is secured at its rearward end to the inverted U shaped member 38 which embraces roller 9 and is secured to the shaft thereof.

Upon the main supporting frame I have mounted the bearing member 39 upon which three foot levers 40, 41 and 42 are pivoted, which in turn are hingedly connected to link 43, stirrup 44 and link 45, respectively. The link 43 is also secured to lever 34 near its free end so that by the depression of the pedal end of lever 40 the free end of lever 34 will be elevated and the cutting roller 9 consequently depressed against the surface to be cut and when said lever is released the cutting roller 9 will be elevated through the operation of spring 46. By a depression of the pedal end of lever 42 the free end of lever 33 will be elevated and abrading roller 8 depressed against the surface to be cut and when said lever is released the roller 8 will be elevated through the operation of spring 47. The free ends of levers 33 and 34 overlap and are embraced by the stirrup 44 so that when the pedal end of lever 41 is depressed the free ends of levers 33 and 34 are elevated and both abrading rollers depressed against the surface to be smoothed and with the release of lever 41 springs 46 and 47 operate to elevate the said rollers.

The traction mechanism of my device is shown in Figs. 2 and 3. Upon shaft 19 I have mounted a worm gear 48 disposed to mesh with worm gear 49 rigidly mounted on drive shaft 50. This shaft 50 is secured to the supporting frame by bearings 51 and 52 and carries at its free end a bevel gear 53. Slidably mounted upon shaft 6 is a double bevel gear 54 which is keyed on said shaft against rotation but which slides on ball bearings as shown in Fig. 5. A hand lever 55 is pivoted to the main frame and held in any desired position by the ordinary rack and dog arrangement shown in Fig. 3, while the lower end of said lever 55 is hingedly connected to one arm of bell crank 56 the other arm of which operates to slide the gear wheel 54 back and forth. It is obvious that when gear 53 occupies the position shown in Fig. 2 the traction mechanism will be out of gear and the transmission

mechanism may be thrown in advance gear or reverse gear by a suitable manipulation of the hand lever 55.

It will be observed from the above specifications and the accompanying drawings 70 that I have provided a device of the character described having a plurality of abrading rollers, rotatable in the same direction and having a single driving chain. These rollers are also capable of being elevated 75 and depressed either simultaneously or separately thus permitting either one or both to operate upon the surface to be smoothed, at the will of the operator, features which are not common in this class of machines 80 now in use.

What I claim is:

1. A device of the character described embodying a supporting frame and traction wheels for carrying the same; a motor carried by the frame and operatively connected with the traction wheels; a plurality of abrading rollers carried by the frame and driven by said motor; a means for forcing said rollers into contact with the surface to 85 be smoothed simultaneously and means whereby the rollers may be forced to contact with said surface separately.

2. In a floor surfacing machine, the combination of a vehicle mounted on wheels; 95 abrading rollers rotatable in the same direction, pivotally mounted on said vehicle and movable toward and from the surface to be operated on; a motor on the vehicle for operating the rollers for imparting traction motion to the vehicle; a system of levers for moving the abrading rollers toward and from the surface to be operated on either independently or simultaneously; and a transmission mechanism for controlling the 100 forward and backward movement of the vehicle.

3. In a floor surfacing machine the combination with a machine frame and means for supporting said frame on the floor surface, of driven abrading rollers pivotally mounted on the frame and movable either independently or simultaneously toward and from the surface to be smoothed; a mechanism for rotating said rollers in the same direction; a lever mechanism whereby the bodily movement of said rollers may be controlled, and yielding members tending to hold said abrading rollers out of contact 110 with the surface to be smoothed.

4. In a floor surfer, cleaner and polisher the combination of rollers covered with material for acting upon the floors; arms pivoted upon the sides of said device and adapted to hold said rollers and to raise and lower them from the floor; a lever attached to each roller and so fulcrumed as to raise and lower the same; a system of levers for operating upon the first mentioned levers in such 120 a manner as to elevate or lower the rollers 130

- either independently or simultaneously; a motor mounted on said device and having operative connection with a driving chain which in turn is operatively connected with 5 all of the rollers so as to rotate them in the same direction; and a transmission mechanism where forward or rearward movement may be imparted from the motor to the device.
- 10 5. In a floor surfacer, cleaner and polisher, a supporting frame and carriers therefor, a plurality of abrading rollers pivotally mounted thereon and bodily movable toward and from the surface to be smoothed, a lever 15 attached to each roller and fulcrumed to the frame, a system of manually operated levers having connection with said roller levers for operating the same, whereby said abrading rollers may be moved toward and 20 from the surface to be smoothed either independently or simultaneously.
6. In a floor surfacer, cleaner and polisher, a supporting frame and carriers therefor, a plurality of abrading rollers pivotally 25 mounted thereon and bodily movable toward and from the surface to be smoothed, a lever attached to each roller and fulcrumed to the frame, a system of manually operated levers having connection with said roller levers for 30 operating the same, whereby said abrading rollers may be moved toward and from the surface to be smoothed either independently or simultaneously; and yieldable members normally tending to hold the abrading rollers 35 elevated from the surface to be smoothed.
7. In a floor surfacer, cleaner and polisher, a supporting frame and carriers therefor, a plurality of abrading rollers pivotally mounted thereon and bodily movable toward 40 and from the surface to be smoothed, hoods surrounding said rollers, pipes leading from said hoods and uniting in a common discharge, a suction generator carried by said discharge and receptacle for receiving therefrom, a system of operative levers, one for 45 each abrading roller, for elevating and lowering the same, a manually operated lever for each of said operative levers and a manual lever for controlling all of said operative levers simultaneously and a means for 50 operating said abrading rollers.
8. In a floor surfacer, cleaner and polisher the combination of the following instrumentalities, viz:—a frame mounted on carrying 55 wheels, centrally pivoted levers attached thereto, the outer edges thereof supporting abrading rollers revolute thereon, said rollers being covered with an abrasive surface, a system of manually operated 60 levers for controlling said abrading rollers, either independently or simultaneously, through said centrally pivoted rollers, a motor carried by said frame and an operative mechanism driven thereby and having 65 an operative connection with said rollers whereby they are rotated in the same direction, hoods embracing each roller and a suction pipe leading from each hood and uniting in a common discharge pipe, a receptacle for receiving from said discharge, a suction generator carried by said discharge pipe and being operatively connected to the motor, a steering 70 mechanism for said device, means whereby said motor and the traction wheels of said device may be operatively connected in such a manner as to impart either forward or backward movements to said device at the will of the operator.
9. A device of the character described embodying the following instrumentalities, viz:—a frame mounted on carrying wheels, a motor carried thereby, a transmission mechanism for transmitting motion from the motor to said wheels, a steering mechanism for said device, a plurality of abrading rollers pivotally mounted on said frame and bodily movable toward and from the surface to be abraded, a sprocket chain operatively connected to said rollers so as to rotate them 80 in the same direction and also having operative connection with the motor, a lever attached to each of said abrading rollers and fulcrumed to said frame whereby the rollers may be raised and lowered, resilient members operating against said levers and tending to hold said abrading rollers from the surface to be smoothed, manually operated levers having connection with said first mentioned levers whereby the said rollers may 85 90 95 100 be raised and lowered either simultaneously or independently, hoods embracing said rollers, suction pipes leading from said hoods and uniting in a common discharge pipe, a receptacle for receiving from said discharge pipe and a suction generator carried by the last mentioned pipe.
10. In a floor surfacer, cleaner and polisher the combination of the following instrumentalities:—a frame mounted on carrier wheels, an abrading roller pivotally mounted at each end thereof and revolute on their supports, a lever pivotally mounted on the frame for each roller, a manually operated lever also pivoted to the frame for 110 each of the first mentioned levers, and operatively connected therewith, a manually operated lever operatively connected to both of the first mentioned levers for simultaneously operating the same, a motor carried 115 by said frame and an operative mechanism driven thereby and having operative connection with said rollers whereby they are rotated in the same direction, a hood embracing each roller and a suction pipe leading from each hood and uniting in a common discharge pipe, a receptacle for receiving from said discharge, a suction generator carried by said discharge pipe and being 120 125 130 operatively connected to the motor, a steering mechanism for said device, means whereby said motor and the traction wheels of said device may be operatively connected in such a manner as to impart either forward or backward movements to said device at the will of the operator.

ing mechanism for said device, means whereby the motor and the traction mechanism of said device may be operatively connected in such a manner as to impart either forward or rearward movements to the device at the will of the operator.

In testimony whereof I have signed my

name to this specification in the presence of two subscribing witnesses.

WILLIAM E. WARNER.
